FOLDING TABLE WITH PAIRED LEGS

Francis Peter Isherwood and John Wightman
Eeroyd, Millbrook, Stalybridge, England, as-
signors to Woodroyd Tools Limited, Millbrook,
Stalybridge, England, a British company

Application July 16, 1946, Serial No. 683,936
In Great Britain July 25, 1945

4 Claims. (Cl. 311—85)

1

This invention relates to trays as used for domestic and like services and has for its object to provide a simple and readily manipulated construction and arrangement of parts by which the tray can be converted into a table when it has been carried to the position where it is required for use.

A tray in accordance with our invention has a pair of brackets secured upon its underside at each of two ends, such brackets projecting beyond the ends and in each pair of brackets is mounted the centre portion of a U leg construction, the two U legs being capable of being folded against the underside of the tray when the latter is being carried about or is placed upon a support, means being provided for locking the U legs in either position.

According to a further feature of the invention, there is attached to the part of each U leg which comes between the pair of brackets, an arm connected by a link to a rod sliding in guides secured to the underside of the tray, the said rod being notched to engage a locking rib when the U is folded beneath the tray and also when it is projecting vertically downwards from the tray to form two legs to convert the tray into a table.

With our improvement a tray is readily converted into a table without removing the hands from the grips by which the tray is carried. Likewise the table is reconverted to a tray when the grips are held for the purpose of carrying the tray where desired.

The ends of the tray where the grips come may be cut out or recessed to limit the protrusion of the grips from the tray by accommodating the projecting ends of the rods which serve to lock the tray legs folded or extended.

Referring to the accompanying explanatory drawings:

Figure 1 is a perspective view of a device in accordance with the invention.

Figure 2 is a view of the under side of the device.

Figure 3 is a side elevation.

The tray *a* has brackets *b* secured to its under side at each end and mounted rotatably in the brackets are U-shaped members *c*, *d* forming legs. The legs are shown in position to support the tray, and Figure 2 shows in broken lines the position in which they lie against the underside of the tray when it is being carried about. Each U-member *c*, *d* has between the brackets *b* a tubular sleeve *e* which serves as a grip for carrying the tray, and also for turning the legs from one position to the other. The sleeves *e* carry arms *f*, *g* which are connected by links *h*, *i* to rods *j*, *k* sliding in guides

2

l secured to the underside of the tray. The rod *j* has notches *m*, *n* near its ends, and the rod *k* has similar notches *o*, *p*.

When the legs are in the extended position the notches *m* and *p* engage with locking ribs *q* and *r* respectively, and their bevelled ends project beyond the ends of the tray. A slight downward pressure on the ends of the rods releases the notches *m*, *p* from the ribs *q*, *r* and enables the 5 grips *e* to be turned to move the legs into the folded position. The rods *j*, *k* then take up the positions shown in broken lines in Figure 2, and the notches *n*, *o* engage with the locking ribs *r*, *q* respectively. In this way the legs are locked in 10 each position, but can be easily released by pressure on the ends of the rods, which are placed so as to be within easy reach of the thumbs when the sleeves *c* are held in the hands.

What we claim is:

- 20 1. A tray for domestic and like services, comprising a top, brackets secured to the top at each of two ends, two rods rotatably mounted in the brackets, one rod at each end of the tray, legs rigidly connected with the rods at right angles thereto, and adapted to extend at right angles to the top and to be swung to lie against the underside of the top by rotating the rods, guides on the underside of the top, two bars mounted in the guides so as to be slidable in a direction at right angles to the rods, each bar being notched near each end and each bar being of a length greater than half the length of the top, an arm on each rod extending at right angles thereto approximately parallel to the legs, two links, each 25 pivoted to the end of one arm and pivotally attached to one of the bars so as to slide the bar when the rod is rotated, each bar being arranged so that in the position of the rod in which the legs extend at right angles to the top, one of the 30 ends of the bar projects beyond one end of the top, and in the position of the rod in which the legs lie against the underside of the top, the other end of the bar projects beyond the other end of the top, and locking ribs on the underside of the top for engaging the notches of the bars in the extreme positions thereof.
- 35 2. A tray as claimed in claim 1, in which the rods are formed with grip portions for carrying the tray and for turning the legs from one position to the other.
- 40 3. A tray as claimed in claim 2, in which the projecting ends of the bars come adjacent to the grip portions of the rods and can be depressed 45 to release them from the locking ribs to enable 50 55

the legs to be turned from one position to the other.

4. A tray for domestic and like services, comprising a top, brackets secured to the top at each of two ends, two rods rotatably mounted in the brackets, one rod at each end of the tray, legs rigidly connected with the rods at right angles thereto, and adapted to extend at right angles to the top and to be swung to lie against the underside of the top by rotating the rods, guides on the underside of the top, two bars mounted in the guides so as to be slidable in a direction at right angles to the rods, each bar being notched near each end, an arm on each rod extending at right angles thereto approximately parallel to the legs, two links, each pivoted to the end of one arm and pivotally attached to one of the bars so as to slide the bar when the rod is rotated, each bar being arranged so that in the position of the rod in which the legs extend at right angles to the top, 10 15 20

one of the ends of the bar projects beyond one end of the top, and in the position of the rod in which the legs lie against the underside of the top, the other end of the bar projects beyond the other end of the top, and locking ribs on the underside of the top for engaging the notches of the bars in the extreme positions thereof.
